UNITED STATES PATENT OFFICE

128,801

DESIGN FOR A MITTEN

Newton J. Rice, Fairhaven, N. J., assignor to Wimelbacher & Rice, New York, N. Y.

Application March 1, 1941, Serial No. 99,283

Term of patent 14 years

To all whom it may concern:

Be it known that I, Newton J. Rice, a citizen of the United States and a resident of Fairhaven, in the county of Monmouth and State of New Jersey, have invented a new, original, and ornamental Design for a Mitten, of which the following is a specification, reference being had to the accompanying drawing, forming part thereof, in which—

Fig. 1 is a plan view of the palm portion of a mitten, showing my design;

Fig. 2 is an edge view thereof;

Fig. 3 is a view of the back portion of the mitten.

I claim:

The ornamental design for a mitten, substantially as shown.

NEWTON J. RICE.
